UNITED STATES PATENT OFFICE.

GEORGE E. HATCH, OF MERIDEN, CONNECTICUT, ASSIGNOR TO THE
MERIDEN FLINT GLASS COMPANY, OF SAME PLACE.

DESIGN FOR A FRUIT-BOWL.

SPECIFICATION forming part of Design No. 13,300, dated September 19, 1882.
Application filed August 16, 1882. Term of patent 7 years.

To all whom it may concern:

Be it known that I, GEORGE E. HATCH, of Meriden, in the county of New Haven and State of Connecticut, have invented a new Design for Fruit-Bowls; and I do hereby declare the following, when taken in connection with accompanying drawing and the letters of reference marked thereon, to be a full, clear, and exact description of the same, and which said drawing constitutes part of this specification, and represents a perspective view.

This invention relates to a design for fruit bowls or stands, with special reference to table ornamentation; and the design consists in the configuration as shown in the accompanying illustration.

The fruit-bowl is designed to be made in glass, but may be of other material. The base is circular in form, its edge turned up, giving it a concavo-convex shape, the concave side up. The edge of the plate is scalloped, the outer surface ground representing rose and lozenge shaped figures, as shown in the accompanying illustration. The body of the bowl is hemispherical in shape, the convex side resting on a base in the center of the plate, the surface of the base ornamented by a series of annular ribs. The top or mouth edge of the

bowl is scalloped, the surface of the bowl cut, representing rose and lozenge shaped ornaments, as shown in the accompanying illustration.

The plate may be employed for other ornaments—as, for instance, flower-vases. I therefore do not wish to limit the use of the plate to this particular bowl, or the bowl to this particular plate, it only being essential to either that an equivalent for the other shall be present.

I claim—

1. The design for plate for table ornamentation, consisting of the concavo-convex shape, having its edge scalloped and its surface cut in rose and lozenge shaped ornamentation, as shown in the accompanying illustration.

2. The design for fruit-bowl, consisting of the hemispherical-shaped bowl resting on a base in its plate, the upper edge of the bowl scalloped, and the surface ornamented with rose and lozenge shaped ornaments, as shown in the accompanying illustration.

GEO. E. HATCH.
